UNITED STATES PATENT OFFICE.

OTIS R. ANGELL, OF HAVERHILL, MASSACHUSETTS, ASSIGNOR TO HAMEL SHOE MACHINERY COMPANY, A CORPORATION OF MASSACHUSETTS.

EDGE-SETTING MACHINE.

1,305,864.

Specification of Letters Patent. Patented June 3, 1919.

Application filed November 12, 1917. Serial No. 201,522.

To all whom it may concern:

Be it known that I, OTIS R. ANGELL, a citizen of the United States, residing at Haverhill, in the county of Essex and State 5 of Massachusetts, have invented certain new and useful Improvements in Edge-Setting Machines, of which the following is a specification, reference being had therein to the accompanying drawings.

10 This invention relates to machines for setting and burnishing the edges of shoe soles and more particularly to means for supporting and for reciprocating the operating tool.

15 In machines of the above type as at present constructed and in which cranks or eccentrics have been employed for reciprocating the tools, much annoyance has been caused by reason of the excessive vibration 20 produced, resulting in disagreeable noise and rapid wear of parts. It is an object of the present invention to so construct a machine of the above type as to eliminate all unnecessary machine parts and at the same 25 time to reduce undesirable vibration to a minimum.

It is a further object of the invention to provide in an edge setting machine a tool holder constructed to simultaneously hold a 30 plurality of tools and adapted to be so controlled as to present either of said tools in working position at the will of the operator.

Other and additional objects and advantages of the present invention together with 35 desirable details of construction and improved combination of parts will be herein-after described and particularly pointed out in the claims.

Figure 1 is a front elevation of the head 40 of the machine showing the parts in operative position, certain parts being broken away to show details of construction. Fig. 2 is a side elevation of the tool-holding head, and adjacent parts. Figs. 3 and 4 are corresponding views of a modified form of the 45 device, and Fig. 5 is a detail of a wear compensating device.

1 indicates a frame or head which may be of any desired construction. This head is 50 provided with suitable bearings for a shaft 2, said shaft being driven continuously from a convenient source of power, the details of the drive mechanism being omitted herein as forming no part of the present invention. 55 Loosely mounted upon a projecting end of

said shaft 2 is a supporting-member 3, said supporting-member being herein shown as in the form of a disk having integral therewith or attached thereto a gear 4. At a point 5 upon the member 1 is pivotally 60 mounted a sector arm 6, said sector arm being provided at 7 with a rack meshing with the gear 4.

At a point 8 upon said arm 6 is a latch-member of any suitable or well known type 65 adapted for engagement with locking openings in a guide-member 11 fixed upon said head 1. By manipulation of latch-member 8 the arm 6 may be freely swung to the right or left about its pivotal support and locked 70 at the end of its movement by engagement of the latch with either of said openings. By the swinging movement of the arm 6 from one extreme position to the other the gear 4 may be rotated substantially one-half 75 revolution and may be locked in either of two diametrically opposed positions, the purpose of which will be hereinafter described. While the above mechanism for rotating the gear 4, and locking it is well 80 adapted for use in this machine, it is to be understood that the invention is in no manner limited thereto, as any other equivalent device may be substituted therefor. No specific claims are made herein to the lock- 85 ing and turning devices.

Projecting from the end of shaft 2 is an eccentric pin 10, said pin engaging within a suitable journal opening in a block 12, said block being provided with upper and 90 lower machined bearing surfaces. At one side of shaft 2 and spaced therefrom a pin or shaft 13 projects from the face of said support 3, said pin being held in fixed relation within said support by means of set 95 screw 14 or other suitable equivalent means, the pin being provided at its outer end with a head 15. Between said head and the support 3 a tool-carrying head 16 is pivotally supported upon the pin 13 to rock thereon, 100 said head being provided with a pair of spaced apart arms 17 and 18 extending in the direction of the shaft 2. The arms 17 and 18 provide opposed bearing surfaces 19, 20 for engagement with the correspond- 105 ing bearing surfaces of the block 12, thus permitting a free sliding movement of the block with respect to the head 16.

Projecting upwardly and downwardly from said head 16 are posts 21, 22 carrying 110

at their extremities members 23 and 24 respectively adapted for the mounting thereon of the usual tool holders employed in this type of machine. The posts 21 and 22 may, 5 if desired, be slotted as at 25 to make the parts lighter and save material in manufacture, this, however, not being a necessary part of the invention.

The operation of the mechanism above 10 described will now be obvious. With the parts shown in the position of Fig. 1 rotation of the shaft 2 will cause the block 12 to move in a circular path. By reason of the 15 slideable engagement of the block with the bearing surfaces of the head 16, the latter will be caused to rock or vibrate upon the pin 13, thereby causing the desired movement of the tool holders. As in machines of this character it is desirable to employ 20 different tools upon the shank and forepart of the shoe, the opposed tool-holding members 23 and 24 have been provided, and by movement of the arm 6 by proper manipulation of the latch-member 8, the support 3 25 may be so turned about the shaft 2 as a center as to reverse the position of the tool holders, thereby permitting the use of either of the tools at the will of the operator.

While the above is a preferred embodiment of the invention the devices shown in 30 Figs. 3 and 4 may be at times found desirable. As in these figures many of the parts correspond in structure and function to those of the form hereinbefore described, it will be only necessary to describe such parts briefly as follows:—2^a is the drive shaft; 3^a the supporting member; 4^a the gear fixed thereupon; 13^a the pintle pin; 40 14^a the set screw therefor; 16^a the tool-carrying head; 23^a and 24^a the members for carrying the tool holders and 10^a the eccentric pin projecting from the end of the shaft.

In the present embodiment of the invention the tool-holding head 16^a is provided with opposed arms 21^a and 22^a having portions 30 and 31 extending in the direction of the shaft 2^a. The parts 30 and 31 are slotted at 40 to provide opposed arms and 50 between said arms are pivoted, as by means of pins 32, 33, a pair of rolls 34, 35, said rolls being arranged for direct contact with the eccentric pin or cam 10^a. It is to be understood that suitable means may be provided for turning the gear 4^a through 180 degrees and for locking the same in either extremity of its movement as in the previously described embodiment.

The operation of the present modification 60 will now be clear. Upon rotation of the shaft 2^a the eccentric pin 10^a contacting with rolls 34 and 35 will cause an upward and downward swinging movement of the same about the pintle pin 13^a, thus causing a rocking movement of the head and the tool

holders carried thereby. Reversal of the tools for alternative operation of the same will be brought about in the manner hereinbefore described with respect to the preceding modification.

70

Having now thus described the invention and a specific embodiment thereof as well as the function and mode of operation of the same, what I claim as new and desire to secure by Letters Patent of the United States is,

75

1. In an edge setting machine a normally stationary support, a tool-holding head pivoted to rock thereon, means for rocking said head, and manually adjustable means for turning said support thereby to permit selective employment of the tools by the operator.

80

2. In an edge setting machine having a rotary drive shaft, a normally stationary support carried thereby, a tool-holding head mounted to rock on said support and carrying a plurality of tools, and means for turning said support about said shaft to permit selective employment of the tools by the operator.

85

3. In an edge setting machine, a rotary drive shaft, a support mounted to rotate thereon, a tool-holding head carried by said support, means to vibrate said tool-holding head from said drive shaft, and means to hold said support stationary.

90

4. In an edge setting machine, a rotary drive shaft, a support mounted on said shaft, a vibrating tool-holding head carried by said support, an arm projecting from said head, and means carried by said shaft and engaging said arm constructed and arranged to rock said arm in opposite directions to vibrate said head.

95

5. In an edge setting machine having a rotary drive shaft, a support concentric with said shaft, a tool-holding head pivoted upon said support to rock in a plane perpendicular to the axis of the shaft, an eccentric pin upon said shaft, and means interposed between said head and said pin whereby rotation of the shaft serves to rock said head.

100

6. In an edge setting machine a normally stationary support, a tool-holding head adapted to hold a plurality of tools and pivoted to rock thereon, means for rocking said head, and means for adjusting said support to permit the employment of any of said tools in the edge setting operation.

105

7. In an edge setting machine, in combination, a drive shaft, a sleeve loosely mounted thereon and constituting a support, a multiple tool-holding head pivoted upon said support, means carried by the shaft for rocking said head, and means for rotating the sleeve about the shaft and for locking the same in desired positions.

110

8. In an edge setting machine having a rotary drive shaft, a normally stationary

115

120

125

support carried thereby, a tool-holding head pivoted to rock thereon, said head being provided with a pair of opposed guiding surfaces, a block mounted to slide upon said surfaces, and means carried by the drive shaft for moving said block in a circular path.

9. In an edge setting machine having a rotary drive shaft, a normally stationary support mounted thereon, a tool-holding

head pivoted to rock thereon and having a pair of laterally extending arms providing opposed guiding surfaces, a block engaging between said surfaces and slideable thereon, a journal opening in said block, and an eccentric fixed to the shaft and within said journal opening.

In testimony whereof, I have signed my name to this specification.

OTIS R. ANGELL.
